UNITED STATES PATENT OFFICE.

EDMUND NOLAN, OF DETROIT, MICHIGAN.

GREASE-CUP.

1,353,607.

Specification of Letters Patent. Patented Sept. 21, 1920.

Application filed March 11, 1920. Serial No. 364,923.

To all whom it may concern:

Be it known that I, EDMUND NOLAN, a citizen of the United States of America, residing at Detroit, in the county of Wayne 5 and State of Michigan, have invented certain new and useful Improvements in Grease-Cups, of which the following is a specification, reference being had therein to the accompanying drawings.

10 This invention relates to grease cups and has for one of its objects the provision of a construction which can be readily attached to or detached from a lubricating connection and in which the pressure upon the 15 grease in the barrel is automatically relieved before releasing the clamping pressure upon the lubricating connection. Other objects of the invention reside in the novel arrangements and combinations of parts as 20 more fully hereinafter set forth.

In the drawings:

Figure 1 is a central longitudinal section partly in elevation of a construction embodying my invention;

25 Fig. 2 is a central longitudinal section of one-half the construction and showing the parts in different positions of adjustment;

Fig. 3 is a central section through the coöperating ratchets in separated position;

30 Fig. 4 is a side elevation of the clamp at right angles to that shown in Fig. 1.

1 is the spindle having the outer and inner threaded ends 2 and 3 respectively and the intermediate enlarged cylindrical portion 4, and the axial bore 5 therethrough for the passage of the grease. 6 is the barrel having the outer closed end 7 and the base 8, the latter being rotatably mounted upon the intermediate portion 4 of the spindle. 40 This intermediate portion is provided with the annular flange 9 forming the lateral face 10 for limiting the outward movement of the barrel relative to the spindle.

The base 8 has the cylindrical flange 11 which is threadedly engaged by the barrel proper 12, the latter having the shoulder 13 which is engageable with the outer end of the cylindrical flange to limit the engaging movement of the barrel proper with the flange. 50 The cylindrical flange 11 is of such a length as to retain the plunger 14 when it is desired to remove the barrel proper to fill the same with grease and then replace the barrel proper.

55 The plunger 14 comprises the cup 15

formed of suitable material, such as leather, and the disks 16 on opposite sides thereof, these disks being rigidly secured against the cup by means of the flange 17 upon the hub 18. This hub threadedly engages the outer 60 end 2 of the spindle and the cup has frictional engagement with the wall of the barrel sufficient to rotate the plunger about the threaded end 2 and thereby move the same longitudinally thereof. 65

19 is a clamp for securing the grease cup to the lubricating connection 20, the latter having the longitudinal passageway 21 connected into by the transverse passageway 22, which latter is adapted to register with the axial bore 5 in the spindle 1. This clamp has the outer end 23 which threadedly engages the inner end 3 of the spindle and the transversely apertured end 24, the aperture being polygonal and adapted to engage a 75 correspondingly shaped end of the lubricating connection 20. 25 is a shoulder or pin upon the lubricating connection and engageable with the apertured end 24 of the clamp to limit the engaging movement of 80 the lubricating connection and grease cup whereby the transverse passageway 22 will be alined with the axial bore 5 in the spindle.

As thus far described, upon rotation of 85 the barrel 6 to the right or in a clock-wise direction the barrel proper 12, plunger 14, spindle 1, and barrel base 8 rotate as a unit, the inner end 3 of the spindle rotating in the threaded end 23 of the clamp 19 moving 90 inward upon the lubricating connection 20. When the clamping pressure of the inner end 3 of the spindle upon the lubricating connection 20 becomes greater than the friction between the plunger 14 and outer 95 threaded end 2 of the spindle the plunger will be then rotated about the spindle, the latter remaining stationary, and thereby moved outwardly relative thereto to force the grease through the axial bore 5 of the 100 spindle and into the lubricating connection.

For the purpose of sealing the joint between the inner end 3 of the spindle and the lubricating connection the packing 26 is provided carried in the inner end of the 105 spindle and surrounding the axial bore 5.

For the purpose of relieving the pressure upon the grease in the barrel before releasing the clamping pressure between the inner end 3 of the spindle and the lubricating 110

connection 20 the outer and inner ratchets 27 and 28 are provided surrounding the spindle 1 and in substantial alinement with the barrel base 8. The outer ratchet 27 is fixedly secured to the intermediate portion 4 of the spindle while the inner ratchet is non-rotatably secured to the threaded portion 23 of the clamp, as by means of the pin or key 29 extending through a side wall of 10 the ratchet and engaging in the longitudinal groove 30 in the threaded portion 23. 31 is a coil spring abutting an annular flange 32 upon the threaded portion 23 and the outer end of the ratchet 28 whereby the teeth 15 of the inner ratchet are yieldably maintained in engagement with the teeth of the outer ratchet. These teeth are so arranged as to permit of rotation of the outer ratchet 27 to the right or in a clock-wise direction 20 relative to the inner ratchet 28, but upon rotation of the outer ratchet to the left or in a counter clock-wise direction the teeth will lock.

For the purpose of disengaging the teeth 25 of the outer and inner ratchets 27 and 28, respectively, the sleeve 33 is provided surrounding the barrel base 8 and secured thereto, the inner end of this sleeve being adapted to engage the inner ratchet 28 and move 30 it inwardly relative to the outer ratchet when the pressure upon the grease in the barrel is relieved and the barrel moves inwardly.

To lock the barrel, including the barrel 35 proper 12 and barrel base 8, to the outer ratchet 27 upon rotation of the barrel to the left or in a counter clockwise direction the shoulder members 34 and 35 are provided in concentric relation to the axis of the 40 spindle 1 and extending in opposite directions respectively from the barrel base and outer ratchet. These shoulder members as shown in the present instance comprise pins 45 which are provided with inclined ends permitting of rotation of the barrel base relative to the outer ratchet in a clockwise direction.

Assuming the parts to be in secured position as shown in Fig. 1 in which the barrel 50 proper 12 is loaded with grease and screwed upon its base 8 and the inner end 3 of the spindle 1 is clamped to the lubricating connection:—

By turning the barrel proper 12 to the 55 left or in a counter-clockwise direction the inner ratchet 28, which is in engagement with and locked to the outer ratchet 27 by means of the ratchet teeth, causes the spindle 1, the outer and inner ratchets 27 and 60 28 respectively, the clamp 19 and the lubricating connection 20 to act as one unit thereby eliminating the possibility of the spindle turning in the clamp before the plunger 14 and barrel 6 have rotated relative to the 65 spindle. Thus, during the first portion of

the rotation of the barrel to the left or in a counter clockwise direction the plunger will be rotated therewith and moved inwardly upon the spindle thereby relieving the pressure upon the grease in the barrel. 70 Upon continued rotation of the barrel to the left or in a counter clockwise direction the barrel proper 12, the plunger 14, and the barrel base 8 rotate relative to the spindle causing the barrel, the barrel base and the 75 sleeve 33, secured to the barrel base, to move inwardly toward the lubricating connection due to the fact that the barrel moves inwardly relative to the spindle upon relieving of the pressure upon the grease in the 80 barrel. This inward movement causes the sleeve to engage with the inner ratchet 28 and move the same out of engagement with the outer ratchet 27, as shown in Fig. 2. The shoulder members 34 and 35 upon the 85 barrel base 8 and outer ratchet 27 lock, whereby the barrel proper 12, the barrel base 8, the spindle 1 and the outer ratchet 27 operate as a unit, so that continued counter clock-wise rotation of the barrel will 90 move the inner end 3 of the spindle outwardly relative to the clamp 19 thereby releasing the clamping pressure upon the lubricating connection.

What I claim as my invention is:

1. The combination with a lubricating connection, of a grease cup including the spindle detachably clamped to said connection and means for automatically relieving the pressure upon the grease in said cup 100 prior to detaching said cup including the spindle from said connection.

2. The combination with a lubricating connection, of a grease cup including the spindle detachably clamped to said connection, and means operated by the rotation of said cup in one direction for automatically relieving the pressure upon the grease in said cup and subsequently unclamping said cup including the spindle 110 from said connection.

3. The combination with a lubricating connection, of a grease cup detachably clamped thereto, means operated by the rotation of said cup in one direction to clamp 115 said cup to said connection and to subsequently force the grease in said cup into said connection and means operated by the rotation of said cup in the opposite direction to relieve the pressure upon the grease in said 120 cup and to subsequently unclamp said cup from said connection.

4. The combination with a lubricating connection, of a grease cup comprising a spindle engageable with said connection, a 125 barrel rotatably mounted on said spindle, a plunger movable within said barrel and movable longitudinally of said spindle, said plunger being actuated by said barrel and means actuated by said barrel for clamping 130

said spindle to said lubricating connection prior to longitudinal movement of said plunger relative to said spindle.

5. The combination with a lubricating connection, of a grease cup detachably secured thereto comprising a spindle engageable with said connection, a barrel rotatably mounted on said spindle, a plunger within said barrel and movable longitudinally of said spindle, said plunger being actuated by said barrel, a clamp coöperating with said spindle to secure said grease cup to said lubricating connection, said spindle, barrel, and plunger forming a unit movable relative 10 to said clamp prior to longitudinal movement of said plunger with respect to said spindle upon rotation of said barrel in one direction, means for connecting said clamp, spindle and lubricating connection to form 15 a unit upon rotation of said barrel in the opposite direction to provide opposite longitudinal movement of said plunger with respect to said spindle, and means operable upon continued rotation of said barrel in 20 the opposite direction for subsequently unclamping said grease cup.

6. The combination with a lubricating connection, of a grease cup detachably secured thereto, comprising a spindle having 25 an end engageable with said connection, a barrel rotatably mounted on said spindle, a plunger within said barrel and frictionally engaging the side wall thereof, said plunger threadedly engaging said spindle, a clamp 30 threadedly engaging said spindle at its connection end and having a portion surrounding said connection, a ratchet non-rotatably secured to said clamp, a coöperating ratchet non-rotatably secured to said spindle, means 35

upon said barrel for longitudinally moving 40 said first-mentioned ratchet to disengage the same from said second-mentioned ratchet, and means upon said barrel and last-mentioned ratchet for subsequently locking the former to the latter upon rotation of the 45 former in one direction.

7. The combination with a lubricating connection having a polygonal end, of a grease cup detachably secured thereto, comprising a spindle having an end engageable 50 with the polygonal end of said connection, a barrel base rotatably mounted on said spindle, a barrel proper upon said base, a plunger within said barrel proper and adapted to be actuated thereby, said plunger threadedly engaging said spindle, a clamp having a portion threadedly engaging the connection end of said spindle and a second portion surrounding the polygonal 55 end of said connection, a ratchet non-rotatably secured to said clamp and movable longitudinally thereof, means for yieldably maintaining said ratchet in extended position, a second ratchet non-rotatably secured to said spindle and normally in engagement with 60 said first-mentioned ratchet, coöperating shoulder members upon said barrel base and second-mentioned ratchet adapted to lock said barrel base to said second-mentioned ratchet upon rotation of said barrel proper 65 in one direction, a sleeve surrounding said barrel base and movable longitudinally of said spindle to engage said first-mentioned ratchet and disengage the same from said second-mentioned ratchet. 70 75

In testimony whereof I affix my signature.

EDMUND NOLAN.
